UNITED STATES PATENT OFFICE

SAMUEL J. JOHNSON, OF CINCINNATI, OHIO, ASSIGNOR TO THE SEINSHEIMER PAPER COMPANY, OF CINCINNATI, OHIO, A CORPORATION OF OHIO

WINDOW SHADE

Application filed March 29, 1930. Serial No. 440,084.

This invention relates to paper window shades.

The general idea of paper window shades has much to recommend it, in that they are cheap, can be frequently changed without a great expense, and lend themselves readily to an infinite variety of patterns and color schemes. Color is becoming more and more in demand throughout industry as well as

10 throughout interior decoration, and the plain drab appearance of the conventional window shade is tending to decrease its use very materially. There is, however, one very severe drawback inherent in the idea 15 of paper window shades. Paper is possessed of a grain. The paper has greater resistance to stresses applied in line with the grain than it has to stresses applied transversely to the grain. Therefore, if the 20 paper be applied to the roller with the grain parallel to the roller the shade has the very decided tendency to tear. If, on the other hand the shade be applied to the roller with the grain transverse or at right angles to the 25 roller, the paper has a tendency to curl, or retain the curvature imparted to it by the roller.

The object of this invention is to provide a paper window shade adapted to be attached 30 at the top to a roller and at the bottom to a stick, adapted to be of any color or to bear any ornamental design, possessed of sufficient strength to withstand the strain to which it is to be subjected in use, yet characterized by flexibility sufficient to cause it to hang vertically from the roller without curving, bending or curling.

Other objects and further advantages will be more fully set forth in the accompanying 40 drawings, in which:

Figure 1 is a view showing a window shade constructed according to the present invention and applied to a window.

Figure 2 is a perspective view of the rear 45 side of the shade showing the preferred way in which the shade is attached to the roller and to the bottom stick.

The window shade of this invention comprises a length of relatively strong paper 1 50 adapted to be attached at the top to the win-

dow shade roller 2. The grain runs transversely or at right angles with the roller. The tendency of the paper to curl is corrected by means of embossing or minute creasing applied to the paper transversely to the grain, the effect of which is to break the grain to a degree sufficient to cause it to hang vertically without tendency to curl.

As disclosed, an ornamental design has been applied to one side of the shade, the 60 embossing or minute creasing not having been sufficient to impart to the surface of the paper a roughness or unevenness inhibitory to the applying of the design to the shade by press-room methods. Since the pull upon the 65 shade in use is parallel to the grain the shade does not have a tendency to tear at the edges and yet since the grain is broken or impaired by the transverse embossing or minute creasing the shade does not have a tendency to 70 curl.

Across the bottom of the shade is secured a strip of gum paper 3. As disclosed in Figure 2, the bottom of the shade is looped around the stick 4 to which a window shade 75 cord 5 is attached, and the one edge of the gum paper adhesively secured to the back of the shade. Across the top of the shade is likewise a strip of gum paper 6, one edge of which may be attached to the window shade 80 roller as disclosed in Figure 2.

The embossing or minute creasing is indicated on Figure 2 by transverse lines 7. The grain on the paper on the other hand is not readily visible and its direction is indicated by the double-headed arrow on Figure 2.

The window shades of this invention can be fabricated cheaply, are susceptible to being produced in an infinite variety of colors and ornamental designs, can be readily replaced or changed when soiled, are durable, and roll and unroll satisfactorily upon the conventional window shade roller.

Having described my invention, I desire 95 to be limited only by the ensuing claims:

1. A window shade adapted to be used upon a roller, said window shade, comprising, a length of paper adapted to be secured to the roller with its grain running transversely 100

to the roller, said paper characterized by minute creasing transverse to the grain and of sufficient relief to dispossess the paper of all tendency to maintain the curl imparted to it by the roller.

5 2. A new article of manufacture, comprising, a length of paper having at one end thereof a gummed strip adapting said length of paper to be secured to a window shade roller, the grain of said length of paper running at right angles to said gummed strip and embossing transverse to the grain of the paper.

10 3. A window shade, comprising, a length of paper minutely creased transversely to the grain sufficiently to destroy the tendency of the paper to curl, without destroying the receptivity of the surface to a printed design.

15 4. A window shade, comprising, a length of paper, provided with minute creasing transverse to the grain of the paper.

20 5. In combination, a window shade roller, a paper window shade adhesively secured to the roller, the grain of said paper running at right angles to the roller, minute creasing transverse to the grain of the paper, a bottom stick about which the lower end of the shade is looped, and an adhesive member maintaining said loop.

25 30 6. A new article of manufacture, comprising, a length of paper, one end of which is adapted to be secured to a window shade roller, and minute creasing substantially parallel to the end adapted to be attached to the roller.

35 In witness whereof, I hereunto subscribe my name.

SAMUEL J. JOHNSON.
